(57) CLAIM

The ornamental design for a video game case, as shown and described.

DESCRIPTION

FIG. 1 is a perspective view of a video game case showing my new design in a closed position;

FIG. 2 is a top view thereof;

FIG. 3 is a bottom view thereof;

FIG. 4 is a front view thereof;

FIG. 5 is a rear view thereof;

FIG. 6 is a left view thereof;

FIG. 7 is a right view thereof;

FIG. 8 is a perspective view of FIG. 1 shown in an open position;

FIG. 9 is a top view thereof;

FIG. 10 is a bottom view thereof;

FIG. 11 is a rear view thereof;

FIG. 12 is a front view thereof;

FIG. 13 is a left side view thereof; and,

FIG. 14 is a right side view thereof.

The broken lines indicate unclaimed portions of the design and form no part of the claimed design.

1 Claim, 11 Drawing Sheets
